Patented Dec. 30, 1919.

UNITED STATES PATENT OFFICE.

DON H. HAYDEN, OF CLEVELAND, OHIO.

SWITCH-BOX OR OUTLET-BOX.

1,326,498.

Specification of Letters Patent. Patented Dec. 30, 1919.

Application filed January 12, 1917. Serial No. 141,920.

To all whom it may concern:

Be it known that I, DON H. HAYDEN, a citizen of the United States, residing at Cleveland, in the county of Cuyahoga and State of Ohio, have invented a certain new and useful Improvement in Switch-Boxes or Outlet-Boxes, of which the following is a full, clear, and exact description.

This invention relates to certain new and useful improvements in the so-called switch boxes or outlet boxes of the type composed of one or more units designed to be inserted in the wall of a building to receive a wall switch, and provided with openings or knock-out plugs through which the conductors may be extended.

The principal object of the invention is to decrease the cost of producing and assembling these switch boxes, and at the same time to provide a construction which is strong, durable and efficient.

More specifically considered, the invention aims to provide a construction such that there is eliminated entirely the necessity for screws to fasten together the parts of a single or multiple unit box, and to lock and fasten the parts together in such a manner that the latter can be quickly assembled or disassembled.

Another of the more specific objects is to so dispose locking tongues, lugs or tabs and corresponding receiving openings, or slots, that there is a minimum waste of material in forming the parts of the box by stamping them out of sheet metal.

The invention may be briefly summarized as consisting in certain novel details of construction and combinations and arrangements of parts which will be described in the specification and set forth in the appended claims.

In the accompanying sheet of drawings wherein I have shown the preferred construction and also a slightly modified construction, Figure 1 is a perspective view of what I term a double unit box, one of the end pieces of the box being removed; Fig. 2 is a similar view of a complete single unit box; Fig. 3 is a top plan view of the same; Fig. 4 is a transverse sectional view of the lower part of the box, the section being taken substantially along the line 4-4 of Fig. 3; Fig. 5 is a perspective view of the lower part of a box showing a slight modification in the form of the lower or bottom fastening means; and Fig. 6 is a sectional

view similar to Fig. 4, showing the construction of Fig. 5.

The box embodying my invention is of a shape well known to those familiar with this art, and is provided preferably with knock-out plugs, the purpose of which is well understood. This box is composed of one or more substantially U-shaped pieces 10, which form the sides and bottom or body 60 of the box, and of two end pieces 11. In a single unit box as shown in Fig. 2, the box is formed of one U-shaped piece 10 and the two end pieces, and with a multiple unit box such as illustrated in Fig. 1, the box is 70 composed of two or more of the U-shaped pieces 10, fastened together in the manner illustrated, together with the two end pieces which are fitted or fastened to the pieces 10 in the same manner that the latter 75 are fastened together.

The present invention resides solely in the novel means for fastening the parts together and in the arrangement or disposition of the fastening parts as will now be 80 explained.

It will be observed that each pair of units or parts 10, and that each end piece is fastened to the adjacent part 10 at the upper corners and at the bottom of these pieces, 85 that is to say, the parts are fastened together along the upper edges and along the bottom of the box. The upper fastening means between each adjacent pair of pieces 10, 10 or 10, 11, includes two locking tongues 90 12, at opposite corners of the piece 10 or 11 as the case may be, and two notches or slots 13 at the corners of the opposite companion piece and arranged to receive the ends of the tongues as clearly illustrated in the 95 drawings, the tongues extending in an end-wise direction laterally from the piece or wall on which the tongues are formed and then being bent laterally, the ends of the tongues extending just through the slots and 100 being substantially flush with the outer sides of the box. Additionally each pair of adjacent parts of the box, whether the parts be two adjoining pieces 10, or an end piece 11 and adjacent piece 10, are fastened 105 together at the bottom of the box by a tongue or tab 14 which is offset to extend either under the bottom portion of the adjoining piece as in Figs. 1 to 4, or over the same as in Figs. 5 and 6, and to be locked 110 thereto by a stamped lug or projection 15 on the tongue. Each locking lug or projec-

tion 15 either inclines upwardly from the face of the tongue 14 as in Figs. 1 to 4, or downwardly from the face of the tongue as in Figs. 5 and 6, and each lug 15 is provided at the end of the inclined face with a sharp shoulder or inner face designed to engage and hold the companion piece in position when the latter has been moved inwardly over the inclined surface of the lug 15 past the shoulder. As will appear more fully subsequently, the locking lug 15 on one piece 10 engages the lower outer face of one of the end pieces 11, in which event the corresponding tongue may pass between a pair of centering lugs 16 of the end piece shown in Fig. 2, and the remaining pieces of the box are held together by the lug on one piece snapping into an opening 17 in the bottom of the adjoining piece. 20 One important feature of this box is that the locking tongues 12 and 14 are all formed on the same edge, or project in one direction from the piece, whereas the opposite edge is plain in the sense that it has no projecting tongues, but only the slots or openings formed to receive the tongues on the companion or adjacent piece. As will now be apparent, this arrangement results in less waste of material than would be the case if both edges or ends of the piece were provided with outwardly extending locking tongues or projections. 25

To explain more in detail the exact disposition of the locking parts, it may be stated that one end piece 11 has at its upper corners two of the upper locking tongues 12, and is provided at the bottom with one of the locking tongues or tabs 14, all these tongues projecting in the same general direction from the plane of the piece 11. The part 10 which is adjacent the end piece 11 is provided at two of its upper corners with slots 13 which receive the upper tongues 12 of the end piece 11, and it is provided at the bottom with an opening 17 (see Figs. 1, 3 and 4) which receives the upstanding punched lug 15 on the tongue 14 of the end piece 11. At the opposite end of the piece 10 being described, the part 10 is provided with two of the locking tongues 12 which enter slots either of the adjoining or adjacent piece 10 of Fig. 1, or in the other end piece 11 of Fig. 2. The same end of the part 10 is provided in addition to the two tongues 12 with the bottom tongue 14 which extends under the second piece 10 of Fig. 1, so that the upstanding lug 15 will project up into the opening 17 of the adjoining or second piece 10 of Fig. 1, or under the bottom edge of the end piece 11 of Fig. 2 so that the lug 15 will extend upwardly from the bottom edge and hold the same in position. In the event there are two of these pieces 10, they will be formed precisely alike and will be fastened together in the

manner described. The second end piece 11 is provided with no projections or tongues but simply with the two upper corner slots to receive the upper corner tongues 12, and at the bottom it will be formed with the centering lugs 16 between which the tongue 14 of the adjoining piece 10 extends. It will be understood, of course, that there may be more than two of the middle pieces 10 if desired fastened together precisely in the manner described. 75

To assemble the parts the upper corner portions are first fastened together by simply placing the two tongues 12 of one piece into the slots 13 of the adjoining part, then the bottom portions of the pieces are forced together causing one member to ride up onto the inclined lug 15 of the tongue 14 of the adjoining member until the lug 15 either snaps up into the opening 17 or beyond the outer face of said adjoining member. The parts will now be securely locked or held together, no screws being required at all to fasten them together. To take the box apart or to separate any two parts it is only necessary to pry downward slightly the tongue 14 until the companion part can be moved over the lug 15, whereupon the parts will fall apart. In so separating the parts the tongue 14 is not permanently bent but springs back into place so that the parts can be again put together or assembled precisely as before they were taken apart or separated. 90

In the construction illustrated in Figs. 5 and 6, the details of the bottom fastening means are somewhat modified. In this case the tongue designated 14^a does not pass under the adjoining part as in the preferred construction, but over a portion of the adjoining part, and it is provided with a downwardly depressed locking lug, here designated 15^a, which either enters into an opening corresponding to the opening 17 of the first described construction, or engages the outer face of an end piece. As illustrated in Fig. 6, the tongue 14^a on one end piece 11 lies over, or extends into the part 10, and the depressed tongue 15^a extends down into the opening 17. At the opposite end of the box the part 10 has an upwardly offset tongue 14^a which passes through a slot 18 in the second end piece 11, the tongue having a depressed locking lug 15^a over which the end piece 11 is slid so that the lug can snap downward and engage its outer face. The two adjoining pieces 10 of a multiple unit box may be fastened together at the bottom, precisely as illustrated at the right-hand corner of Fig. 6. This construction is similar in principle to that first described, but the former construction is preferable. 110

In both constructions, however, the locking projections on any piece are all on one edge, or project in one direction from the 130

corresponding face or end thereof, leaving the other end free of projecting locking parts. Additionally the parts are fastened together without the necessity for screws, 5 and all parts can be assembled or disassembled quickly and easily. An additional advantage lies in the fact that the parts can be easily formed, no intricate or more expensive dies being required than at the present time.

In consequence this box is cheaper than those on the market at the present time, because it requires somewhat less material, and less time is required to assemble the parts. 15 This saving is a matter of great consequence to manufacturers in view of the fact that the boxes are made in huge quantities.

The box will be provided with any suitable means such as illustrated at 19, for fastening the box to a wall, and any suitable means such as tongues 20, by which the switch may be secured in the box. As these parts are not directly involved in my invention they may be modified as desired, 25 and further description or illustration of the same will be unnecessary.

I do not desire to be confined to the exact details shown, but aim in my claims to cover all modifications which do not involve a departure from the spirit and scope of my invention.

Having thus described my invention, what I claim is:

1. In a switch box or outlet box, one or 35 more middle pieces forming the body of the box and two end pieces fastened thereto, the fastening means between two adjacent parts including a tongue on one part which overlaps the other part, said tongue being provided with an integral offset locking lug which interlocks with said other part, said lug having a face inclined from the face of the tongue and terminating in an abrupt shoulder which said other part engages.

45 2. In a switch box or outlet box, one or more substantially U-shaped middle pieces forming the body of the box and two end pieces fastened thereto, each middle piece having adjacent one edge thereof three openings, two of said openings being adjacent the corners in substantially the planes of the sides thereof and the third opening being in the bottom or base of the piece, and said middle piece having adjacent the other edge three locking tongues, two of said tongues being adjacent the corners and a third at the bottom of the piece, one end piece having a set of tongues which interlock with the stated openings of a middle piece, and the other end piece having portions which interlock with the stated tongues of a middle piece.

60 3. In a switch box or outlet box, one or more substantially U-shaped middle pieces 65 forming the body of the box and two end

pieces fastened thereto, each middle piece having along one edge three openings, two being in the form of open slots adjacent the corners and in substantially the planes of the sides of the piece and a third opening 70 being in the base or bottom of said piece, and said middle piece having adjacent its opposite edge three tongues, two located at the corners of the piece and a third at the bottom or base of the piece, one end piece 75 having tongues which interlock with the stated openings of a middle piece, and the other having portions which interlock with the stated tongues of a middle piece.

4. In a switch box or outlet box, one or 80 more substantially U-shaped middle pieces forming the body of the box and two end pieces fastened thereto, each middle piece having along one edge three openings, two being in the form of open slots adjacent the 85 corners and in substantially the planes of the sides of the piece and a third opening being in the base or bottom of said piece, and said middle piece having adjacent its opposite edge three tongues, two located at 90 the corners of the piece and a third at the bottom or base of the piece, each tongue at the base of the box having an integral offset locking lug, one end piece having tongues which interlock with the stated openings of 95 a middle piece, and the other having portions which interlock with the stated tongues of a middle piece.

5. In a switch box or outlet box, one or 100 more substantially U-shaped middle pieces forming the body of the box and two end pieces fastened thereto, each middle piece having along one edge three openings, two being in the form of open slots adjacent the corners of the piece and a third opening being in the base or bottom of said piece, and said middle piece having adjacent its opposite edge three tongues, two located at the corners of the piece and a third at the bottom or base of the piece, the part of the box 105 adjacent the first named edge of the middle piece having tongues with portions extending into the slots and opening of the middle piece, and the piece adjoining or adjacent the second named edge of said middle piece 110 having portions which receive and interlock with the tongues of said middle piece, each tongue at the bottom of the box having an offset locking lug with a tapered face and an abrupt locking shoulder.

115 6. In a switch box, a substantially U-shaped body composed of one or more pieces or units, said body being provided along one end edge with two open slots arranged adjacent the corners and in substantially the 120 planes of the sides, and at the base with an opening, said body having adjacent the other end edge two locking tongues with ends projecting laterally outward, and having at the bottom a locking tongue with an 125 130

integral offset lug, and two end pieces, one having tongues which project laterally outward and extend into said slots and a tongue provided with an integral lug which enters 5 said opening adjacent one end edge of the body, and the other end piece having two slots which receive the laterally outward

projecting tongues and at the bottom having a portion which interlocks with said lug on the third tongue arranged adjacent 10 the other end edge of the body.

In testimony whereof I hereunto affix my signature.

DON H. HAYDEN.
